DEWAXING WAX-BEARING OIL

William P. Gee, Plainfield, N. J., assignor to Texaco Development Corporation, New York, N. Y., a corporation of Delaware

No Drawing. Application December 13, 1941,
Serial No. 422,879

7 Claims. (Cl. 196—18)

This invention relates to dewaxing wax-bearing oil and particularly to dewaxing oil with a selective solvent mixture composed of a wax anti-solvent liquid and an oil solvent liquid.

The invention broadly contemplates dewaxing wax-bearing oil with a selective dewaxing solvent mixture composed in part of a hydrocarbon mixture consisting mainly of naphthalene, paraffin, aromatic and oxygenated hydrocarbons.

More particularly it contemplates dewaxing with a dewaxing solvent liquid mixture composed of a wax anti-solvent liquid and an oil solvent liquid in which the oil solvent component comprises at least in part a hydrocarbon mixture of naphthalene, paraffin, aromatic and oxygenated hydrocarbons. Advantageously this hydrocarbon mixture comprises a synthetic hydrocarbon mixture composed of a major proportion of naphthalene, paraffin and aromatic hydrocarbons and a minor proportion of oxygenated hydrocarbons which are substantially completely soluble in a saturated aqueous solution of sodium bisulfite at room temperature.

It is already known in the art to dewax wax-bearing oils such as mineral lubricating oils with selective solvents and with selective solvent mixtures which consist of a mixture of a wax anti-solvent liquid such as a low boiling aliphatic ketone and an oil solvent liquid such as benzol and toluol. For example, Govers Patent 1,802,942 discloses dewaxing wax-bearing mineral lubricating oil with a mixture of acetone and benzol, while Govers Patent 2,061,541 discloses dewaxing such oil with a mixture of a ketone, benzol and toluol, the toluol amounting to about 5 to 30% of the mixture. In this latter case the toluol serves to increase the solvent action of the selective solvent mixture upon the oil constituents of the wax-bearing mixture so as to prevent oil separation at dewaxing temperatures of minus 10° F. and below.

The present invention involves dewaxing with a selective solvent mixture of the foregoing type in which the oil solvent component of the solvent mixture consists essentially, or in part, of a hydrocarbon mixture containing little or no toluol. A hydrocarbon mixture which has been found particularly effective for this purpose is that known in the trade as Notol.

In accordance with this invention wax-bearing oil is dewaxed with a dewaxing solvent mixture comprising an aliphatic ketone or other suitable wax anti-solvent liquid and a hydrocarbon mixture such as Notol. Advantageously, the dewaxing solvent liquid may comprise a mixture of

ketone and benzol containing a substantial proportion of Notol, the benzol component being either pure or commercial benzol. In such case the Notol may be substituted for the toluol component of the ketone-benzol-toluol dewaxing solvent mixture referred to in the foregoing Govers Patent 2,061,541.

The hydrocarbon mixture known in the trade as Notol has an A. P. I. gravity of about 43 to 44 and has an initial boiling point of about 160° F. and an end boiling point of about 300° F. by the A. S. T. M. method of distillation. The approximate composition of this hydrocarbon mixture is as follows:

	15	Per cent by volume
Benzene		8.4
Toluene		10.5
Xylene and higher		32.5
20 Naphthalenes		10.9
Paraffins		28.3
Oxygenated hydrocarbons		9.4

The oxygenated hydrocarbons comprise alcohols, ketones and aldehydes substantially completely soluble at about 70° F. in aqueous sodium bisulfite solution consisting of water 80% saturated with NaHSO₃ at about 70° F. The hydrocarbon mixture has a bromine number less than 1 so that it is substantially free from olefins.

30 A hydrocarbon mixture of the foregoing character and composition has a relatively low content of toluene and this is a desirable attribute where the supply of toluene available for industrial solvent uses is scarce or costly. It has also

35 been found that in the case of some wax-bearing oils the foregoing hydrocarbon mixture possesses unexpected advantages as the oil solvent component of a selective dewaxing solvent mixture. Thus, in some cases when dewaxing with a solvent mixture comprising methylethyl ketone and the foregoing synthetic hydrocarbon mixture employing a continuous rotary filter a higher filtration rate is realized and in addition a smaller volume of wash solvent is required to wash the resulting filter cake of wax. Moreover, these advantages are realized without any apparent reduction in the yield of dewaxed oil.

The following data indicate the results obtainable in dewaxing mineral lubricating oil stocks with a selective solvent comprising a mixture of methylethyl ketone, commercial benzol and toluol on the one hand, and with a mixture of methylethyl ketone, commercial benzol and Notol on the other hand.

50 55

Example 1

In this example a steam refined cylinder stock having an A. P. I. gravity of about 24.5, a Saybolt Universal viscosity at 210° F. of about 161 and a pour point of plus 25° F. was mixed with the solvent liquid in the proportion of 4 parts of solvent to 1 part of oil by volume. This mixture was chilled and filtered at a dewaxing temperature of about minus 12° F. The solvent was removed from the resulting filtrate of dewaxed oil and the dewaxed oil was found to have a pour test of about 0° F. In the run with toluol as the third component of the solvent, the solvent liquid consisted of 37% methylethyl ketone, 47.25% commercial benzol and 15.75% toluol. In the companion run the solvent mixture consisted of the same proportions of methylethyl ketone and benzol but contained 15.75% of Notol.

The following is a tabulation of the results obtained as applied to dewaxing on a continuous rotary vacuum filter of the drum type operating so as to maintain a two-minute cycle.

Third component of solvent	A			B		
	Wash ratio	Cycle rate	W. F. O. yield	Wash ratio	Cycle rate	W. F. O. yield
Toluol.....	0	8.68	84.4	0.75	8.95	86.9
Notol.....	0	8.75	85.6	0.63	9.56	87.4

The first pair of runs (A) were made without washing the filter cake and as indicated, the cycle rate, namely, gallons of wax-free oil per square foot of filtering surface per hour is slightly greater when using the solvent containing Notol and in addition the yield of wax-free oil (W. F. O.) expressed as volume per cent basis wax-bearing oil charge is slightly greater. In the second pair of runs (B) the filter cake was washed in each instance with solvent of the same composition, 50% of the permissible wash time being blocked off. In the run with toluol a wash in the proportion of .75 volume of solvent to 1 volume of wax-bearing oil feed was used, while in the run with Notol a slightly lower wash ratio was used. In spite of employing a slightly lower wash ratio the yield of wax-free oil obtained was slightly greater than in the run with toluol and also a higher cycle rate was realized.

Example 2

In this example a wax distillate having an A. P. I. gravity of about 25.4, a Saybolt Universal viscosity of 52.6 at 210° F. and a pour point of plus 85° F. was mixed with the solvent liquid in the proportion of 3 volumes of solvent to 1 volume of wax distillate. The resulting mixture was chilled and filtered at a temperature of minus 20° F. obtaining in each case an oil having a pour test of about 0° F. The solvent composition in each instance was similar to that employed in Example 1, obtaining the following results when operating with a filter cycle of one minute.

Third component of solvent	Wash ratio	Yield W. F. O.	Cycle rate
Toluol.....	1.23	79.1	3.12
Notol.....	1.03	80.5	3.34

As in the case of Example 1 a slightly higher cycle rate with a smaller wash ratio was permitted in the run with solvent containing Notol, while obtaining substantially the same or a slightly

higher yield of dewaxed oil than in the run with solvent containing toluol.

While aliphatic ketones have been specifically mentioned as examples of suitable wax antisolvent liquids it is contemplated that other wax antisolvents may be employed such as benzaldehyde, sulfur dioxide, dichlorethyl ether, and the like.

While specific proportions of wax antisolvent, benzol and Notol have been mentioned in the foregoing examples it is contemplated that the proportions may vary. Thus, when the oil solvent component of the dewaxing mixture consists solely of Notol, the ketone or wax antisolvent constituent of the mixture may range from about 30 to 60% by volume, the remainder being Notol. When a three-component dewaxing mixture, namely, wax antisolvent, benzol and Notol, is employed the composition may also range from about 30 to 60% ketone or wax antisolvent liquid, the remainder being a mixture of commercial benzol and Notol, the Notol comprising from 10 to 50% of this benzol-Notol mixture.

It is contemplated that the solvent mixture of this invention may be employed for separating solid hydrocarbons from various hydrocarbon mixtures of wax concentrates derived from different sources including petroleum, vegetable and animal sources.

Obviously many modifications and variations of the invention as above set forth may be made without departing from the spirit and scope thereof, and therefore only such limitations should be imposed as are indicated by the appended claims.

I claim:

1. In the separation of wax from wax-bearing oil wherein the wax-bearing oil is mixed with a dewaxing solvent mixture comprising a wax antisolvent and an oil solvent mixed in proportion with each other and with the oil such that the solvent mixture exerts selective action as between wax and oil at reduced temperature, the method which comprises mixing the wax-bearing oil with a dewaxing solvent composed of about 30 to 60% wax antisolvent liquid, the remainder being an oil solvent, said oil solvent consisting essentially of a hydrocarbon mixture substantially free from olefins and having an initial boiling point of about 160° F. with an end boiling point of about 300° F., an A. P. I. gravity of about 43 to 44 and comprising mainly naphthene, paraffin, aromatic and a substantial proportion of oxygenated hydrocarbons which are completely soluble in aqueous sodium bisulfite solution consisting of water 80% saturated with NaHSO₃ at about 70° F., chilling the mixture of wax-bearing oil and solvent liquid to a temperature at which wax constituents are solidified, separating solidified wax from the chilled mixture and recovering the solvent liquid from the resulting dewaxed oil.
2. In the dewaxing of wax-bearing oil wherein the oil is mixed with a dewaxing solvent mixture comprising a wax antisolvent and an oil solvent mixed in proportion with each other and with the oil such that the solvent mixture exerts selective action as between wax and oil at the dewaxing temperature, the method which comprises mixing the wax-bearing oil with a dewaxing solvent composed of a wax antisolvent and an oil solvent, said oil solvent comprising a hydrocarbon mixture boiling in the range about 160 to 300° F. and containing about 51% aromatic hydrocarbons, 10.9% naphthene hydrocarbons, 28.3% paraffin hydrocarbons and 9.4% oxygenated hydrocarbons, chilling the mixture of oil and solvent liquid to a dewaxing temperature at

which wax constituents are solidified, separating solidified wax from the chilled mixture and recovering the solvent liquid from the resulting dewaxed oil.

3. The method according to claim 1 in which the wax antisolvent liquid comprises a low boiling aliphatic ketone.

4. The method according to claim 2 in which the wax antisolvent liquid comprises a low boiling aliphatic ketone.

5. In the separation of wax from wax-bearing oil wherein the wax-bearing oil is mixed with a dewaxing solvent mixture comprising a wax antisolvent and an oil solvent mixed in proportion with each other and with the oil such that the solvent mixture exerts selective action as between wax and oil at reduced temperature, the method which comprises mixing the wax-bearing oil with a dewaxing solvent composed of about 30 to 60% wax antisolvent, the remainder being an oil solvent composed of a mixture of commercial benzol and a hydrocarbon mixture boiling in the range about 160 to 300° F., said hydrocarbon mixture comprising 10 to 50% of said remainder and having an A. P. I. gravity of about 43 to 44 and comprising mainly naphthene, paraffin, aromatic and a substantial proportion of oxygenated hydrocarbons which are completely soluble in aqueous sodium bisulfite solution consisting of water 80% saturated with NaHSO₃ at about 70° F., chilling the mixture of oil and solvent liquid to dewaxing temperature at which wax constituents are solidified, separating solidified wax from the chilled mixture and recovering the solvent liquid from the resulting dewaxed oil.

6. The method according to claim 5 in which the hydrocarbon mixture boiling in the range about 160 to 300° F. contains about 51% aromatic hydrocarbons, 10.9% naphthene hydrocarbons,

5 28.3% paraffin hydrocarbons and 9.4% oxygenated hydrocarbons, said oxygenated hydrocarbons being substantially completely soluble in a saturated aqueous sodium bisulfite solution at about room temperature.

10 7. In the separation of wax from wax-bearing oil wherein the wax-bearing oil is mixed with a dewaxing solvent mixture comprising a wax antisolvent and an oil solvent mixed in proportion with each other and with the oil such that the solvent mixture exerts selective action as between wax and oil at reduced temperature, the method which comprises mixing wax-bearing oil with a dewaxing solvent composed of an oxygenated hydrocarbon wax antisolvent liquid, the remainder being an oil solvent, said oil solvent consisting essentially of a hydrocarbon mixture substantially free from olefins, having an initial boiling point of about 160° F. with an end boiling point of about 300° F., and an A. P. I. gravity of about 15 20 25 30 35 43 to 44 and comprising a mixture of naphthene, paraffins, aromatic, and oxygenated hydrocarbons, said oxygenated hydrocarbons being completely soluble in aqueous sodium bi-sulfite solution consisting of water, 80 per cent saturated with NaHSO₃, at about 70° F., chilling the mixture of wax-bearing oil and solvent liquid at a temperature to which wax constituents are solidified, separating solidified wax from the chilled mixture and recovering the solvent liquid from the resulting dewaxed oil.

WILLIAM P. GEE.
